UNITED STATES PATENT OFFICE.

DAVID F. HAYNES, OF BALTIMORE, MARYLAND.

DESIGN FOR A CLOCK-CASE.

SPECIFICATION forming part of Design No. 24,204, dated April 16, 1895.

Application filed February 28, 1895. Serial No. 540,107. Term of patent 3½ years.

To all whom it may concern:

Be it known that I, DAVID F. HAYNES, a citizen of the United States, residing at Baltimore, Maryland, have invented and produced a new 5 and original Design for a Clock-Case, of which the following is a specification, reference being had to the accompanying drawings, forming a part hereof.

Referring now to the drawings, Figure 1 is 10 a front view of the clock case, and Fig. 2 a cross section of the same.

I describe the design thereof as follows: Around the central hole A, at the front, is a bead, *a* concentric with the said hole. The 15 central portion of the sides is hollow or curved, and its edge is decorated with a bead *b* which projects from the face only. From the upper termination of the curved sides is a succession of scallops which meet at the top and 20 center in a slightly overhanging cornice B and the edges are beaded and decorated in a foli-

ated design in relief. At the lower ends of the curved side are reverse curves *c* terminating at the legs C which have hemispherical feet D.

Between the legs C, the bottom of the case is curved and the curves *d* meet at the center in a projection *e*. The edges of the lower portion of the case like those of the upper portion are beaded and decorated with foliated 30 designs in relief.

The width of the case below the curved sides is somewhat greater than the portion above them so as to give a graceful appearance.

I claim as my invention—
The design for a clock case, herein shown and described.

DAVID F. HAYNES.
